UNITED STATES PATENT OFFICE.

WILLIAM F. HIRSCHMAN, OF BUFFALO, NEW YORK.

ROTARY VENTILATOR.

1,416,295.

Specification of Letters Patent. Patented May 16, 1922.

Application filed September 13, 1920. Serial No. 410,025.

To all whom it may concern:

Be it known that I, WILLIAM F. HIRSCHMAN, a citizen of the United States, residing in Buffalo, in the county of Erie and State 5 of New York, have invented new and useful Improvements in Rotary Ventilators, of which the following is a specification.

This invention relates to a rotary ventilator whereby the pressure of the wind or air 10 currents is utilized to draw out or suck objectionable gases and foul air from the buildings, and to discharge the same into the outside atmosphere.

One of the objects of the invention is to 15 produce a device of this character which will have the greatest pneumatic-dynamic efficiency for any given wind speed and which will furthermore operate at very low wind pressures. A further object of the invention 20 is to produce a rotary ventilator which will prevent any entrance of rain into the vent pipe, either when rotating or when standing still. A still further object of the invention is to prevent any possibility of a 25 back draft down the vent pipe when the velocity of the wind is extremely high.

In the accompanying drawings:

Figure 1 is a side elevation of the improved rotary ventilator. Figure 2 is a 30 medial section through the axis thereof. Figure 3 is a top plan of the same. Figure 4 is a fragmentary horizontal section looking up and taken on line 4—4, Fig. 2. Figure 5 is also a fragmentary horizontal section, 35 but taken on line 5—5, of Fig. 2.

Similar characters of reference refer to like parts throughout the several views.

9 represents the usual vertical cylindrical vent pipe which is adapted to be connected 40 to any of the piping of a ventilating system (not shown) from which foul air and objectionable gas are drawn and dispelled into the outside air. It is customary to connect this vent pipe to the upper end of a chimney 45 or vertical vent conduit which passes through and projects some distance above the roof of the building which is to be ventilated. Secured to the outer rim or upper edge of said vent pipe and flaring downwardly and outwardly therefrom is an annular deflection ring or skirt 10 which prevents any rising currents of air from curling up and over the upper edge of the vent pipe and thereby tending to cause a back 50 draft down the vent pipe or at least impeding the proper flow of foul air from said

pipe. Arranged within said vent pipe 9 and secured to the inner face thereof are a number of vertical web plates 11, whose inner ends are mutually connected together and 60 collectively act as a support for a vertical hollow tube or bearing sleeve 12. This sleeve as well as the web plates 11 and also the vent pipe 9, are stationary at all times. Secured coaxially to the upper and lower ends 65 respectively of said bearing sleeve 12 are a pair of cup-shaped bearing casings 13 and 14 arranged to receive suitable ball bearings and races which anti-frictionally support a vertical rotatable shaft 15. The upper ball 70 bearings which are received by the upper casing 13 carry, of course, only a radial load, whereas the ball bearings in the lower casing 14 carry both a radial as well as a longitudinal, vertical loading. 75

Secured to the said vertical rotatable shaft 15 and disposed coaxially with respect to the vent pipe 9, is a conical upwardly tapering rotary dome 16. The diameter of this dome is considerably greater than the diameter of 80 the said vent pipe, and from its peripheral edge depends an annular, vertical flange or apron 17, whose lower edge extends some distance below the upper edge of the vertical vent pipe 9. Secured to the lower inclined 85 face of the rotary dome and arranged in a circumferential row are a considerable number of suction blades 18 each of which is inclined somewhat or arranged obliquely relatively to a perpendicular plane passing 90 through the axis and through said suction blade so as to act in the manner of an ordinary propeller blade. Each of these suction blades 18 is secured at its lower end to an annular stiffening ring 20 which is disposed just above and adjacent to the aforementioned skirt 10 of the vent pipe 9, the adjacent faces of said skirt and said stiffening ring being substantially parallel to each other. 95

Connected integrally to the inner ends of a relatively small number of the suction blades 18, are a number of centrifugal blades 21 which are disposed perpendicularly, lying in planes which pass through the axis of 105 rotation of the rotary dome. It will be noticed that the suction blades 18 do not lie above the opening or hole of the vent pipe 10, but are disposed outwardly of the periphery thereof. These vertical, centrifugal blades 21, however extend radially inwardly over the rim of said vent pipe 9 and 110

project beyond the periphery thereof and are disposed above the central opening of said vent pipe. The space above the upper edge of the vent pipe 9 and below the lower 5 face of the dome 16 may be denominated a centrifugal chamber 25 inasmuch as the action of the air currents therein is analogous to the action in the centrifugal chamber of an ordinary centrifugal pump.

10 It is very important however that the air which passes upwardly from the vent pipe into said centrifugal chamber 25 and thence downwardly past the suction blades 18, should not be impeded. It is for this reason 15 that the centrifugal blades are much fewer in number than the suction blades, it being permissible of course, to employ a quite large number of suction blades, inasmuch as the same are disposed a considerable distance 20 outwardly of the axis of rotation of the rotary dome. Any interference of the particular air currents, which pass close to the axis of the dome, is furthermore minimized by cutting off each of the centrifugal blades 25 21 on a line which extends from the inner edge of the stiffening ring 20 up toward the apex of the dome. In this way, the said centrifugal blades only extend radially inwardly a sufficient distance to ensure that the 30 air be caught up from the said centrifugal chamber 25 and ejected therefrom without, however, clogging up said centrifugal chamber or interfering with the free and efficient flow of air therethrough.

35 The rotation of the dome is accomplished by securing a number of propeller buckets or blades 26 to the upper inclined face of the conical, rotary dome 16. For one half of the rotation of the dome these propeller 40 blades are travelling of course, with the wind, and the remaining half rotation against the wind. The construction of the blade, when travelling with the wind involves obviously no difficulties. Therefore, 45 we will deal with the blades when travelling against the wind, i. e., to the left as shown in Fig. 1. Each of these propeller blades has its forward or leading edge 27 disposed substantially flush with the upper surface of the 50 dome, while the main body of each blade extends rearwardly and upwardly from said leading edge and terminates in a trailing edge 28. The intermediate or central portion 30 of the leading edge of each propeller 55 blade is pointed, i. e., it extends some distance forwardly of the rest of the leading edge 27. By this construction the relatively static body of air which lies adjacent the front or outer face of each propeller blade 60 when the blade is travelling against the wind is separated or opened up gradually, such an action being in accordance with accepted pneumatic-dynamic practice. The intermediate portion 31 of the trailing edge 65 28 of each propeller blade overhangs or ex-

tends considerably further rearwardly than the rest of the said trailing edge. This prevents an undue vacuum from forming under the propeller blade when the same is travelling against the wind, as otherwise the 70 rotation of the whole rotary dome would be retarded. This action results from the fact that (as the air starts to flow back over the trailing edge 28 when the blade is moving in the half revolution against the wind) the 75 said air currents first curl over the outer ends of the trailing edge 28, during the time that a partial vacuum is still being formed behind the overhang 31 of the trailing edge. This causes a lateral flow of air 80 toward the under part of the overhang 31, thus effectively killing the vacuum under the entire rear faces of the propeller blades by reason of the lateral air currents so induced. On the other hand, when the propeller blade is travelling with the wind, this overhanging portion 31 cuts the air current and curls the same under the concave or propelling face of the propeller blade similarly to the manner in which the leading 85 edge of an aeroplane wing deflects the air 90 downwardly against the main body of the aeroplane wing.

90 In the operation, the entire dome is rotated by a number of propeller blades 26 whose leading edges 27 are pointed at 30 so as to enter the dead air easily while the central parts of the trailing edges 28 overhang at 31 so as to kill the vacuum under said blades when said blades are travelling against the 100 wind. The foul air from the building which is to be ventilated, rises up the vent pipe 9 into the centrifugal chamber 25. Here it is caught up by a small number of centrifugal blades 21 which however do not project sufficiently into said centrifugal chamber as to impede the flow of air therethrough. Thence the air is deflected downwardly by a large number of suction blades 18 which propel the air in a manner similarly to an ordinary 110 propeller blade, i. e., the blades being inclined to the path of the air flow. These suction blades are arranged entirely outside of the centrifugal compartment so as not to interfere with the flow of air therethrough, 115 the circumferential area of air path being of course much greater where the air travels through the suction blades than it is near the center in the centrifugal chamber 25. The suction blades 18 are located a considerable distance above the lower edge of the annular apron 17 and the space intermediate of said apron and said vent pipe is thereby filled with compressed air which is moving 120 downwardly. Thus any tendency of the outside wind to curl up behind the apron on the particular side which happens, at the time, to be lying toward the oncoming wind, is frustrated, because this wind would have 125 to first rise a considerable distance before 130

coming in contact with the suction blades. Before such an action can occur the dome 16 has had time to turn around sufficiently so that the pressure of the external rising air 5 is lowered on the leeward side of the ventilator and the pressure of the downcoming air from the suction blades rendered sufficient to overcome this rising current. Upward currents of external air are also discouraged by means of the skirt 10 on the upper outer edge of the vent pipe. Thus the ventilator will operate properly even though its lubricating system be neglected so that it turns comparatively slowly. The 15 ventilator will turn, however, in very light breezes, and at no time can any rain come into the vent pipe inasmuch as the same is completely covered.

I claim as my invention:

20 1. A rotary ventilator comprising a rotatable dome, and a propeller blade secured to said dome and having a pointed leading edge and a trailing edge which overhangs the outer surface of said dome, the intermediate 25 portion thereof extending rearwardly more than the other parts of said trailing edge and said intermediate portion being located at a point substantially in circumferential alignment with said leading edge.

30 2. A rotary ventilator comprising a rotatable dome, and a propeller blade secured to said dome and having a pointed leading edge which is located intermediate of the axis and the periphery of said rotatable 35 dome and which terminates flush with the surface of said rotatable dome, said propeller blade having a trailing edge which is disposed outwardly of the surface of said rotatable dome and overhangs rearwardly.

40 40 a line extending from the outer to the inner end of the blade at a point circumferentially in alignment with said leading edge.

3. A rotary ventilator comprising a conical rotatable dome, and a propeller blade 45 whose leading edge is flush with the outer surface of said conical dome and extends forwardly at a point intermediate of the axis and the periphery of said dome, the main portion of said propeller blade extending 50 rearwardly and outwardly away from said leading edge and terminating in a trailing edge which overhangs rearwardly a line extending from the outer to the inner end of the blade at a point intermediate of the axis 55 and the periphery of the dome, substantially as described.

4. A rotary ventilator comprising a vent pipe, a rotatable dome arranged above and covering the upper end of said vent pipe, a 60 centrifugal blade disposed radially with respect to the axis of the rotatable dome and extending from the peripheral part of said dome inwardly over the upper end of said vent pipe.

65 5. A rotary ventilator comprising a vent

pipe, a conical rotatable dome having a depending peripheral apron and mounted sufficiently above the upper end of said vent pipe so as to form a centrifugal chamber, and a vertically disposed flat centrifugal 70 blade secured to the lower face of said dome and extending radially into said centrifugal chamber and over the edge of said vent pipe.

6. A rotary ventilator comprising a vent pipe, a conical upwardly tapering dome 75 mounted coaxially with respect to said vent pipe, a centrifugal blade secured to and extending vertically downwardly therefrom and having an inner edge which extends from approximately the upper rim of the 80 vent pipe obliquely upwardly and inwardly toward the apex of said dome.

7. A rotary ventilator comprising a vent pipe, a conical upwardly tapering rotatable dome provided with an annular downwardly hanging apron which extends below the top of said vent pipe, and a plurality of suction blades secured to the lower face of said dome and disposed inwardly of said 85 apron and outwardly of said vent pipe.

8. A rotary ventilator comprising a vent pipe, a rotatable dome arranged above the upper end of said vent pipe, a circumferential row of suction blades secured to the lower face of said dome and disposed outwardly of said vent pipe, and centrifugal blades extending inwardly over the rim of said vent pipe, said centrifugal blades being comparatively few in number while said suction blades are very numerous.

9. A rotary ventilator comprising a vertical vent pipe, a rotatable, conical dome mounted coaxially therewith and provided with a vertical peripheral apron extending below the upper end of said vent pipe, and a conical skirt secured to the rim of said vent pipe and projecting downwardly and outwardly therefrom.

10. A rotary ventilator comprising a vertical vent pipe, a rotatable conical dome extending below the upper end of said vent pipe and larger in diameter than said vent pipe, and a plurality of suction blades secured to said dome and reversing the direction of flow of the air from said vent pipe, causing said air to be forced vertically downwardly through the space intermediate of the outer face of the vent pipe and the inner face of the dome.

11. A rotary ventilator comprising a vent pipe, a rotatable dome, a stiffening ring arranged coaxially with respect to said dome, a plurality of suction blades and a number of centrifugal blades secured at opposite ends respectively to said stiffening ring and 125 to said dome.

12. In a rotary ventilator, the combination of a vent pipe, a dome rotatably mounted on said vent pipe, a plurality of suction blades secured to said dome and disposed 130

outwardly of said vent pipe, and centrifugal blades also secured to said dome but projecting inwardly over the rim of said vent pipe.

13. A rotary ventilator comprising a vent pipe, a rotatable dome mounted on said vent pipe and provided with an annular apron which depends from the periphery of said dome and which extends below the top of the vent pipe, and a plurality of suction blades secured to said dome above the lower end of said apron, the air from said vent pipe being discharged vertically downwardly from said suction blades and into the space below

which lies intermediate of the outer face of the vent pipe and the inner face of the said 15 apron of the said dome.

14. A rotary ventilator comprising a vent pipe, having a flared skirt extending downwardly and outwardly from its upper rim, a dome mounted coaxially with respect to said 20 vent pipe, a plurality of suction blades secured to the lower face of said dome, and a stiffening ring secured to the lower ends of said blades and disposed adjacent to said skirt of said vent pipe.

WILLIAM F. HIRSCHMAN.
